UNITED STATES PATENT OFFICE

2,028,995

DESULPHURIZING PETROLEUM OILS

Francis M. Rogers, Whiting, Ind., assignor to
Standard Oil Company, Whiting, Ind., a cor-
poration of Indiana

Application December 15, 1928, Serial No. 326,270
Renewed February 23, 1934

1 Claim. (CL 196—27)

This invention relates to the desulphurization of hydrocarbon oils and particularly petroleum distillates of relatively low boiling point.

I have discovered that if such distillates are vaporized and passed through adsorbent clay at a relatively high temperature, the sulphur content is, to a substantial extent, liberated from its combination in the hydrocarbon molecules and may readily be removed by treatment with alkalies and the like.

The method is particularly effective in the case of straight run distillates which contain little or no unsaturated hydrocarbons. More effective desulphurization can be attained with the lower boiling distillates, for example, gasoline, than with the higher boiling distillates such as gas oil and the like.

The temperature at which the clay should be held lies within a broad range. Some sulphur is removed at temperatures as low as 450° F. The optimum temperature is believed to be around 650° F., although higher temperatures of the order of 750° F. or more may be employed.

It is, however, preferred not to employ temperatures above 750° F. because of complications due to cracking.

The invention will be more readily understood from the following description in conjunction with the accompanying drawing, which shows diagrammatically a suitable apparatus for carrying out the process.

Referring to the drawing, 10 is a molten metal bath containing lead or other readily fusible metal or alloy. The bath 10 is located in a suitable setting 11 and is adapted to be heated by a burner 12 or other suitable heating means. Within the bath 10 is located a coil 13 which is supplied with distillate through its inlet 14. The outlet 15 of the coil 13 leads into a receptacle 16 which is adapted to contain a substantial quantity of fuller's earth or other suitable adsorbent clay, designated 17. The outlet 15 leads into one end of the container 16, for example, the upper end, as shown in the drawing. From the opposite end 45 of the container 16, that is, the lower end, as shown in the drawing, an outlet pipe 18 leads to a suitable condenser 19 which is connected to a receiver 20, provided with valved outlets 21 so that the whole apparatus may be maintained under atmospheric, superatmospheric, or subatmospheric pressure, as desired.

Where it is desired to operate under reduced pressure, the outlet 21 is connected to a suitable vacuum pump (not shown). The clay 17 may be suitably supported upon a perforated false bot-

tom 22 in the container 16. The container 16 is located in a suitable setting 23 provided with burners 24 whereby the clay may be maintained at the desired temperature.

The operation of the process will be described by means of a specific example.

Straight run gasoline derived from Winkler crude oil, of end point 420° F., containing 0.19% sulphur and not treated with sulphuric acid or sweetened is passed through the coil 13, completely vaporized therein and brought to a temperature of approximately 650° F. The vapors are passed immediately into the chamber 16 which is substantially filled with raw 30-60 mesh Attapulgus clay maintained at a temperature of 650 to 700° F. throughout. After passing through the clay the vapors are condensed in the condenser 19 and cooled in the receiver 20. The rate of flow is approximately 12 barrels of gasoline per hour per ton of clay. The condensed treated gasoline is subjected to a wash with caustic soda solution to remove sulphuretted hydrogen which becomes disengaged during treatment, and is ready for use without doctor or sulphuric acid treatment.

Under the conditions indicated, the first condensate has a sulphur content of about 0.03%. The sulphur removal becomes progressively less complete but a yield of about 1400 barrels of gasoline per ton of clay may be obtained with an average sulphur content of about 0.06%. The rate of feed may be increased to 20 barrels per hour per ton of clay with only slightly poorer yields and even higher rates may be used when less complete sulphur removal is permissible.

With Olmstead clay the initial sulphur removal is not as complete but the efficiency of this clay for a prolonged time is usually better than that of Attapulgus clay.

Similar runs with straight run gasoline from Panhandle crude oil show a reduction of sulphur content from 0.095% to 0.045% and with straight run gasoline from Lander crude oil 0.215% to 0.079%.

The sulphur removal in the case of petroleum distillates boiling above the gasoline range and in the case of distillates containing substantial quantities of unsaturated hydrocarbons is usually not as effective as in the case of straight run gasoline. Thus, in treating a distillate derived from Winkler crude having a boiling range between 100 and 600° F. with new Olmstead clay at 650° F. the sulphur content in the first runs is reduced from 0.3% to 0.14%. The 420° F. end point gasoline distilled from this product has a sulphur content of 0.07%. A yield of about 2000 barrels

per ton can be obtained with less than 0.1% sulphur. Pressure distillate derived from gas oil from the same crude subjected to liquid phase cracking operations of the Holmes-Manlay or Burton type, when treated in the same manner shows even less complete sulphur removal although substantial quantities of the contained sulphur are removed.

This method of desulphurizing is particularly applicable to distillates which are ordinarily treated with sulphuric acid, sweetened with doctor and re-run with steam or fire and steam. It is particularly advantageous with distillates which require the addition of considerable free sulphur when sweetening with doctor. Such distillates must be redistilled after sweetening and have a considerable tendency to become sour during re-running because of the decomposition of disulphides. The product of the clay treatment appears to contain little or no disulphides. In the case of distillates of wide boiling range which must be redistilled to remove high boiling point fractions, the redistillation may be effected with little or no steam without the product becoming sour.

Although the present invention has been described in connection with the details of a specific example thereof, it is to be understood that such details are not intended to be limitative of the invention except in so far as set forth in the accompanying claim.

In the claims hereinafter made, the term "solid adsorbent catalytic material of the clay type" is intended to exclude pumice, activated charcoal, coke, silica gel, fireclay and the like, none of which resemble adsorbent clay.

I claim:

The process of refining gasoline containing as impurities sulphur compounds difficult to remove in the ordinary manner which comprises converting said difficultly removable sulphur compounds into easily removable sulphur compounds by contacting said gasoline in the vapor form with solid adsorbent catalytic material of the clay type at a temperature of from 650° to 750° F. at a flow rate of 12 to 20 barrels of oil per hour per ton of catalyst, cooling and condensing the treated vapors and treating them to remove said easily removable sulphur compounds.

FRANCIS M. ROGERS. 21
